N. Y., a corporation of New York

Application May 2, 1942, Serial No. 441,499

8 Claims. (Cl. 204—91)

This invention relates to manufacture of alkali metal ferricyanide. For convenience, the principles of the improvements are described mostly in connection with production of potassium ferricyanide.

In commercial practice, electrolytic oxidation of potassium ferrocyanide to the ferricyanide is carried out in a cell equipped with an anode and a cathode surrounded by a porous ceramic diaphragm forming the cathode chamber. On passage of current thru the cell, production of potassium ferricyanide is understood to take place in accordance with the following:

On completion of electrolysis, finished anolyte solution—predominantly potassium ferricyanide contaminated with potassium ferrocyanide and potassium hydroxide—is withdrawn from the cell, cooled to crystallize potassium ferricyanide, and filtered to recover potassium ferricyanide crystals. The mother liquor filtrate resulting from such crystallization contains varying quantities of potassium ferricyanide and ferrocyanide, and substantial amounts of potassium hydroxide. This mother liquor is then used in some way or other in the make-up of another potassium ferrocyanide solution to be supplied to the electrolytic cell for a succeeding operation.

From the above equation it will be noted that, as electrolytic oxidation proceeds, for every mol of potassium ferricyanide formed one mol of KOH is also produced. In practice, approximately half of this KOH is retained in the cathode chamber while the balance of such KOH works thru the porous walls of the diaphragm into the anolyte solution which, when finished, is withdrawn from the cell. Hence, the mother liquor resulting from crystallizing potassium ferricyanide out of an anolyte solution contains a substantial quantity of potassium hydroxide which was produced during electrolysis. Mother liquor of high potassium hydroxide concentration cannot be used in making up a subsequent ferrocyanide starting solution without first getting rid of some of the potassium hydroxide in order to prevent a detrimental build-up of this compound in the liquors in the system. As far as I am aware, all prior proposals, directed to reduction of potassium hydroxide concentration of potassium ferricyanide liquors, involve treatment of such liquors with potassium hydroxide neutralizing agents which, because of their compositions and characteristics, result in introduction of foreign compounds into the circulating liquors. Presence of these impurities gives rise to difficulties which can be offset only more or less by frequent and cumbersome recrystallization of the potassium ferrocyanide crystals in order to obtain a product of

reasonable purity. Hence, reduction of potassium hydroxide concentration of ferricyanide solutions has been a problem in the art.

One of the principal objects of this invention is provision of a process for lowering the alkali metal hydroxide concentration of alkali metal ferricyanide liquors without introducing undesirable impurities into such liquors and without requiring losses of alkali metal or cyanide values.

5 I have found that the objects of the invention may be accomplished by treating alkali metal ferricyanide-ferrocyanide-hydroxide liquors with certain agents which function to convert the alkali metal of the excess or undesired alkali metal hydroxide to alkali metal iron-cyanide compounds which are soluble and remain in solution in the treated liquor, and to convert the hydroxide component of the excess alkali metal hydroxide to an iron hydroxide precipitate which may be removed 15 from the treated solution by simple filtration. Thus, I am enabled to neutralize or lower the alkali metal hydroxide content of liquors to any extent desired, to suit the particular operation at hand, and transform the alkali metal constituent 20 of the alkali metal hydroxide so neutralized to a soluble alkali metal iron-cyanide and remove from the system the hydroxide radical of the alkali metal hydroxide so neutralized, all without introducing into the operation any material which adversely affects the purity of the ultimate products, and without causing loss of alkali metal or 25 cyanide values as by liquor bleed-off.

Practice of the invention comprises treating a liquor, of the type described and containing an 30 undesired amount of alkali metal hydroxide with a treating agent reactable with alkali metal hydroxide to form soluble alkali metal iron-cyanide and to precipitate iron hydroxide. More particularly I have found that suitable treating agents 35 are iron salts, of an acid of the group consisting of ferro and ferri cyanic acids, such salts being reactable with the alkali metal hydroxide contained in the liquors treated to form soluble alkali metal iron-cyanide and to precipitate iron hydroxide. Examples of suitable neutralizing or 40 treating agents are Prussian blue, understood to be ferric ferro cyanide, $Fe_4(Fe(CN)_6)_3$; Turnbull's blue, understood to be ferrous ferricyanide, 45

50 $Fe_3(Fe(CN)_6)_2$;

and a more or less white iron salt, understood to be ferrous ferrocyanide, $Fe_2Fe(CN)_6$.

In carrying out the invention, in apparatus such as illustrated diagrammatically on the accompanying flow sheet and for example as applied to manufacture of potassium ferricyanide, when starting operation a potassium ferrocyanide solution may be formed in make-up tank 10 by dissolving in water $K_4Fe(CN)_6 \cdot 3H_2O$ crystals in 55 quantity to form a substantially saturated so-

lution. As known in the art, a potassium ferrocyanide as fed into the anolyte chamber 11 of an electrolytic cell 12 should contain a certain amount of potassium hydroxide, the function of which is primarily to prevent corrosion of the anode and secondarily to promote conductivity of the anolyte solution. Hence, a desired amount of potassium hydroxide from an external source may be added to the potassium ferrocyanide solution, and a typical starting solution made up without use of mother liquor from a previous operation may comprise from 150 to 250 g. p. l. of $K_4Fe(CN)_6$ and from 2 to 10 g. p. l. of KOH. It is noted that when forming a potassium ferrocyanide starting solution as in tank 10, whether such solution is made up from $K_4Fe(CN)_6 \cdot 3H_2O$ crystals and extraneous potassium hydroxide or from $K_4Fe(CN)_6 \cdot 3H_2O$ crystals and potassium ferricyanide-ferrocyanide-hydroxide mother liquor from a previous operation, such starting solution is made up so as to have what may be referred to as a predetermined KOH concentration which may vary for instance from 2 to 25 g. p. l., depending upon the nature of the particular operation.

The starting solution is run into the anolyte chamber of a cell provided preferably with a nickel anode and with a steel cathode surrounded by a porous ceramic diaphragm 13 forming a cathode chamber 14. Circulation of solution in the anolyte chamber, and a solution temperature of the order of 40-50° C. may be maintained by any convenient means. Ordinarily, during the progress of oxidation, temperature should not exceed 50° C. in order to prevent decomposition of ferricyanide to iron hydroxide, and temperature may be kept as high as say 40° C. to avoid crystallization of potassium ferricyanide. The cathode chamber is filled with a weak solution of KOH which functions primarily as a conductor between the cathode and the walls of the surrounding porous diaphragm. When the current is turned on, reaction proceeds in accordance with the above Equation (1) and potassium ferricyanide is formed. As previously noted, during the course of reaction in the cell one mol of KOH is formed for every mol of potassium ferricyanide produced, about half of the KOH thus formed remaining in the cathode chamber, the balance of such KOH working its way thru the porous walls of the diaphragm and into the anolyte solution. The improvements constituting the present invention are primarily directed toward removal from the system, at a latter stage, of preferably that portion of potassium hydroxide which is contained in the finished anolyte and which was produced during oxidation.

On completion of oxidation to the extent desired, the anolyte solution at temperature of, e. g., 40-50° C. is filtered in filter 16 to separate any solids, and the filtrate is run into a cooler and crystallizer 17. A typical filtered anolyte solution may contain from 350 to 400 g. p. l. of $K_4Fe(CN)_6$, from 20 to 37 g. p. l. of $K_4Fe(CN)_6$, and from 15 to 32 g. p. l. of KOH. The anolyte solution is cooled to room temperature and agitated for 6-8 hours to effect crystallization of $K_4Fe(CN)_6$ product which is filtered out in filter 18 and suitably dried.

As a result of this filtration operation, there is produced in line 20 a potassium ferricyanide mother liquor containing some potassium ferrocyanide and also some KOH the total of which is made up of (a) the KOH fed into the anolyte chamber

with the incoming potassium ferrocyanide starting solution plus (b) that portion of the KOH which was produced during oxidation and which is present in the finished anolyte solution as withdrawn from the cell. A representative mother liquor filtrate may comprise 260 to 300 g. p. l. of $K_4Fe(CN)_6$, 20 to 37 g. p. l. of $K_4Fe(CN)_6$, and 17 to 33 g. p. l. of KOH.

In accordance with the preferred embodiment of the invention, such a mother liquor is treated in tank 22 with one of the previously mentioned agents to neutralize a desired amount of KOH and lower the KOH content of the mother liquor to such a degree that the liquor may be used in forming another potassium ferrocyanide make-up solution for a succeeding operation of the electrolytic cell. The preferred extent of KOH content reduction of a given body of mother liquor will be understood from consideration of the operating expedient that in commercial processes of the type described, it is desired to feed into the anolyte chamber of the cell or battery of cells a potassium ferrocyanide which contains an above mentioned predetermined concentration of potassium hydroxide, specific KOH concentration being dependent upon the particular control conditions employed. Hence, in carrying out the present improvements the preferred extent of KOH neutralization is regulated so that the total body of mother liquor, after partial neutralization and as returned thru line 23 to the potassium ferrocyanide solution make-up apparatus 10, contains an amount of KOH such that a succeeding make-up solution (formed by addition of, e. g., $K_4Fe(CN)_6 \cdot 3H_2O$ crystals to mother liquor) has the operator's desired predetermined KOH concentration. Viewed from another angle, extent of KOH neutralization of a total body of mother liquor is such as to neutralize a quantity of KOH which approximately corresponds with that portion of potassium hydroxide which was contained in the finished anolyte and which was produced during oxidation. In other words, the preferred embodiment of the invention as to extent of KOH neutralization gets rid of the normal KOH build-up taking place during one complete passage of liquor thru the system.

I find that the most satisfactory treating or neutralizing agent is Prussian blue,

which when added to a potassium ferricyanide mother liquor containing potassium hydroxide reacts with potassium hydroxide in accordance with the following:

(2)

Thus, the potassium of the neutralized potassium hydroxide is converted back to soluble potassium ferrocyanide which is the essential constituent of a starting solution fed into an electrolytic cell, and the hydroxide content of the neutralized potassium hydroxide is converted to ferric hydroxide which may be filtered out of the partially neutralized liquor as by filter 24. In the case of treatment of a given body of a particular mother liquor, it will be understood that the preferred amount of KOH to be neutralized is approximately the difference between the KOH concentration of the mother liquor in line 20 as discharged from the potassium ferricyanide crystal filter and the previously mentioned predetermined KOH concentration of a potassium ferrocyanide

solution to be fed into the electrolytic cell. Hence, the amount of KOH to be neutralized may be found by liquor analysis, and the theoretical quantity of treating agent needed may be readily calculated. In operation, it is preferred to use an excess of about 5 to 10% by weight of treating agent over the calculated theoretical requirement. For example, in the case of Prussian blue, best results are obtained when using about 1.4-1.5 parts by weight for every part of KOH to be neutralized.

I further find that to facilitate the neutralizing reaction in tank 22 and obtain a satisfactorily filterable iron hydroxide precipitate, the treating operation should be carried out at temperatures from about 35° C. to not more than 50° C. Since the mother liquor from the potassium ferricyanide filter 18 is usually at room temperature, it is preferred to heat up the mother liquor, prior to treatment with the neutralizing agent, to within the temperature range indicated. The neutralizing agent is then added and the mass is agitated for from say 10 to 20 minutes during which time the reaction indicated by equation (2) takes place and proceeds to completion. Thereafter the liquor is filtered to remove the iron hydroxide, and the partially neutralized filtrate is returned to the potassium ferrocyanide make-up solution apparatus. In one example of practice of the process a mother liquor containing about 273 g. p. l. of $K_3Fe(CN)_6$, about 26.2 g. p. l. of $K_4Fe(CN)_6$ and 29.2 g. p. l. of KOH was agitated for 15 minutes at a temperature of 40° C. with 1.45 parts by weight of Prussian blue per part of KOH to be neutralized. The liquor was filtered and the clear filtrate contained 22.6 g. p. l. of KOH.

In practicing the invention, as applied for example to neutralization of mother liquor, it is not necessary to subject an entire body of such liquor to actual contact with neutralizing agent. To illustrate, a half portion of a given body of mother liquor may be treated with the full quantity of neutralizing agent needed to effect the desired extent of neutralization of the total body of mother liquor. On completion of neutralization, and following filtration of the treated half portion of mother liquor, the resulting filtrate and the untreated portion of the mother liquor are combined, and as is apparent the KOH concentration of the composite is the same as would have been the case had the entire body of mother liquor been treated. This procedure has the advantage, in some operations, of avoiding heating up and filtering the entire volume of mother liquor.

Thus far the KOH neutralizing operation has been described in connection with treatment of mother liquor resulting from filtering out of potassium ferricyanide crystals. The potassium hydroxide concentration reduction feature of the invention may be applied similarly to liquor at any convenient point in the system. For example, the needed quantity of treating agent may be added to the potassium ferricyanide anolyte solution as at 25 immediately after discharge of the same from the anolyte chamber of the electrolytic cell. In this instance, the iron hydroxide precipitate is removed by the filter 16 along with extraneous solids, to provide a clear anolyte solution preparatory to crystallization. However, since solubility of $K_3Fe(CN)_6$ in the solution decreases with increase of KOH content, treatment of the anolyte chamber effluent liquor with KOH neutralizing agent necessarily lowers KOH concentration and correspondingly reduces the potassium ferricy-

anide crystal crop from a liquor subsequently fed into the potassium ferricyanide cooling and crystallizing apparatus. Accordingly, reduction of KOH content of this point in the liquor circuit is not as desirable as the previously discussed mother liquor treatment.

When Turnbull's blue or ferrous ferrocyanide are used as neutralizing agents, the reactions taking place are much the same as previously indicated and apparently proceed respectively as follows:

However, it is preferred to use Prussian blue as it has been found that the resulting iron hydroxide precipitate is more readily filterable. The next overall most satisfactory treating agent is Turnbull's blue.

The principles of the invention are also applicable to neutralization of the sodium hydroxide content of sodium ferricyanide liquors produced by electrolytic oxidation of sodium ferrocyanide. In this operation, a sodium ferrocyanide solution containing sodium hydroxide is electrolytically oxidized to produce a sodium ferricyanide anolyte containing some unoxidized sodium ferrocyanide and the NaOH initially fed into the anolyte chamber plus the NaOH formed during oxidation and present in the anolyte solution as withdrawn from the anolyte chamber, such oxidation of sodium ferrocyanide being generally comparable with the previously described oxidation of potassium ferrocyanide. However, in the case of the sodium ferricyanide anolyte solution, often it is desirable to completely remove the sodium hydroxide, and hence in accordance with 40 the invention the quantity of treating agent employed may be that required to completely neutralize the NaOH content of the anolyte liquor and form an iron hydroxide precipitate and a corresponding quantity of soluble sodium ferrocyanide. After treatment of the solution with a treating agent, e. g., preferably Prussian blue at temperatures of 35-50° C. and with agitation, the anolyte solution is filtered to separate out precipitated iron hydroxide and form a sodium ferricyanide filtrate containing more or less sodium ferrocyanide.

My copending application Serial No. 441,500, filed May 2, 1942, is directed to a particular process for making sodium ferricyanide.

I claim:

1. The process for making alkali metal ferricyanide comprising forming a starting solution containing alkali metal ferrocyanide, electrolytically oxidizing said alkali metal ferrocyanide solution under conditions to form alkali metal ferricyanide liquor containing alkali metal hydroxide, treating alkali metal ferricyanide liquor containing alkali metal hydroxide with an iron salt, of an acid of the group consisting of ferro- and ferri-cyanic acids, reactable with alkali metal hydroxide to form soluble alkali metal iron-cyanide and to precipitate iron hydroxide, thereby reducing the alkali metal hydroxide content of said liquor and converting alkali metal constituent of alkali metal hydroxide to soluble alkali metal iron-cyanide, separating iron hydroxide from said liquor, and returning soluble alkali metal iron-cyanide constituent of the resulting separated liquor to the subsequent starting solution.

2. The process for making alkali metal ferricyanide comprising forming a starting solution containing alkali metal ferrocyanide, electrolytically oxidizing said alkali metal ferrocyanide solution under conditions to form alkali metal ferricyanide liquor containing alkali metal hydroxide, treating alkali metal ferricyanide liquor containing alkali metal hydroxide with Prussian blue reactable with alkali metal hydroxide to form soluble alkali metal ferrocyanide and to precipitate iron hydroxide, thereby reducing the alkali metal hydroxide content of said liquor and converting alkali metal constituent of alkali metal hydroxide to soluble alkali metal ferrocyanide, separating iron hydroxide from said liquor, and returning soluble alkali metal ferrocyanide constituent of the resulting separated liquor to the subsequent starting solution.

3. The process for making potassium ferricyanide comprising forming a starting solution containing potassium ferrocyanide, electrolytically oxidizing said potassium ferrocyanide solution under conditions to form potassium ferricyanide liquor containing potassium hydroxide, recovering solid potassium ferricyanide from said solution, treating resulting potassium ferricyanide mother liquor containing potassium hydroxide with an iron salt, of an acid of the group consisting of ferro- and ferri-cyanic acids, reactable with potassium hydroxide to form soluble potassium iron-cyanide and to precipitate iron hydroxide, thereby reducing the potassium hydroxide content of said mother liquor and converting potassium constituent of potassium hydroxide to soluble potassium iron-cyanide, separating iron hydroxide from said mother liquor, and returning the residual liquor containing soluble potassium iron-cyanide to the subsequent starting solution.

4. The process for making potassium ferricyanide comprising forming a starting solution containing potassium ferrocyanide, electrolytically oxidizing said potassium ferrocyanide solution under conditions to form a potassium ferricyanide anolyte liquor containing potassium hydroxide produced during said oxidation, withdrawing finished anolyte solution from the oxidizing zone, recovering solid potassium ferricyanide from said anolyte solution, treating resulting potassium ferricyanide mother liquor containing potassium hydroxide produced during said oxidation with an iron salt, of an acid of the group consisting of ferro- and ferri-cyanic acids, reactable with potassium hydroxide to form soluble potassium iron-cyanide and to precipitate iron hydroxide, thereby reducing the potassium hydroxide content of said mother liquor and converting potassium constituent of potassium hydroxide to soluble potassium iron-cyanide, the quantity of said salt being such as to effect reduction of the potassium hydroxide content of the total mother liquor by an amount approximately corresponding to that portion of potassium hydroxide which was contained in said finished anolyte and which was produced during said oxidation, separating iron hydroxide from said mother liquor, and returning the residual liquor containing soluble potassium iron-cyanide to the subsequent starting solution.

5. The process for making potassium ferricyanide comprising forming a starting solution containing potassium ferrocyanide, electrolytically oxidizing said potassium ferrocyanide solution under conditions to form a potassium ferricyanide anolyte liquor containing potassium hydroxide 75

produced during said oxidation, withdrawing finished anolyte solution from the oxidizing zone, recovering solid potassium ferricyanide from said anolyte solution, agitating resulting potassium ferricyanide mother liquor containing potassium hydroxide produced during said oxidation at temperature of 35-50° C. with a Prussian blue reactable with potassium hydroxide to form soluble potassium ferrocyanide and to precipitate iron hydroxide, thereby reducing the potassium hydroxide content of said mother liquor and converting potassium constituent of potassium hydroxide to soluble potassium ferrocyanide, the quantity of Prussian blue being such as to effect reduction of the potassium hydroxide content of the total mother liquor by an amount approximately corresponding to that portion of potassium hydroxide which was contained in said finished anolyte and which was produced during said oxidation, separating iron hydroxide from said mother liquor, and returning the residual liquor containing soluble potassium ferrocyanide to the subsequent starting solution.

6. The process for making potassium ferricyanide comprising forming an initial potassium ferrocyanide starting solution having a predetermined concentration of potassium hydroxide, electrolytically oxidizing said potassium ferrocyanide solution under conditions to form a potassium ferricyanide anolyte liquor containing potassium hydroxide produced during said oxidation, withdrawing finished anolyte solution from the oxidizing zone, recovering solid potassium ferricyanide from said anolyte solution, treating resulting potassium ferricyanide mother liquor containing potassium hydroxide with an iron salt, of an acid of the group consisting of ferro- and ferri-cyanic acids, reactable with potassium hydroxide to form soluble potassium iron-cyanide and to precipitate iron hydroxide, thereby reducing the potassium hydroxide content of said mother liquor and converting potassium constituent of potassium hydroxide to soluble potassium iron-cyanide, the quantity of said salt being such as to effect reduction of the potassium hydroxide content of the total mother liquor by an amount such that when said total mother liquor is used to form a subsequent starting solution, the potassium hydroxide concentration of such subsequent starting solution approximately corresponds with the potassium hydroxide concentration of said initial starting solution, separating iron hydroxide from said mother liquor, and returning the residual liquor containing soluble potassium iron-cyanide to the subsequent starting solution.

7. The process for making alkali metal ferricyanide comprising forming a starting solution containing alkali metal ferrocyanide, electrolytically oxidizing said alkali metal ferrocyanide solution under conditions to form alkali metal ferricyanide liquor containing alkali metal hydroxide, treating alkali metal ferricyanide liquor containing alkali metal hydroxide with material of the group consisting of Prussian blue and ferrous ferrocyanide, reactable with alkali metal hydroxide to form soluble alkali metal ferrocyanide and to precipitate iron hydroxide, thereby reducing the alkali metal hydroxide content of said liquor and converting alkali metal constituent of alkali metal hydroxide to soluble alkali metal ferrocyanide, separating iron hydroxide from said liquor, and returning soluble alkali metal ferrocyanide constituent of the resulting separated liquor to the subsequent starting solution.

8. The process for making potassium ferricyanide comprising forming a starting solution containing potassium ferrocyanide, electrolytically oxidizing said potassium ferrocyanide solution under conditions to form potassium ferricyanide liquor containing potassium hydroxide, recovering solid potassium ferricyanide from said solution, treating resulting potassium ferricyanide mother liquor containing potassium hydroxide with Prussian blue reactable with potassium hy-

droxide to form soluble potassium ferrocyanide and to precipitate iron hydroxide, thereby reducing the potassium hydroxide content of said mother liquor and converting potassium constituent of potassium hydroxide to soluble potassium ferrocyanide, separating iron hydroxide from said mother liquor, and returning the residual liquor containing soluble potassium ferrocyanide to the subsequent starting solution.

HANS R. NEUMARK.
